UNITED STATES PATENT OFFICE.

BERNARD McGRODER, OF CLEVELAND, OHIO.

TUYERE.

SPECIFICATION forming part of Letters Patent No. 396,102, dated January 15, 1889.

Application filed October 17, 1888. Serial No. 288,330. (No model.)

To all whom it may concern:

Be it known that I, BERNARD McGRODER, of Cleveland, in the county of Cuyahoga and State of Ohio, have invented a certain Im-
5 proved Double-Valve-Bottom Blast Tuyere-Iron, of which the following is a specification.

The object of the improvements is to render the tuyere-iron more powerful and durable, and to be readily freed from ashes or cinders
10 which may accumulate within the chamber of the tuyere-iron; to provide means by which a circulation of air is induced through the fire as may be required when the blast is not applied, and in making the tuyere-iron with a
15 hollow tuyere valve and stem, both for lightness and to cause a current of air to pass through the said valve to prevent its burning out.

That the invention may be fully understood, 20 reference will be had to the following specification and annexed drawings.

Figure 1 illustrates a vertical section of the said tuyere-iron. Fig. 2 is an inverted plan view thereof, and Fig. 3 represents a front side 25 view.

Like letters designate like parts in the drawings and specification.

The air-chamber A is provided with a base or flange, a, (which may be either square or 30 round,) by which means it is set and held in position in connection with the forge. The interior is preferably of a parabola form or parabolic curve, with corresponding exterior. Near the bottom of the air-chamber A is an opening, b, Fig. 1, which is the terminus of the induction blast-pipe F, and at the crown or top of said chamber is the air outlet or opening c. Said opening c is controlled by the air-valve B. The upper part of this valve coincides with 35 the walls of the air-chamber and is pointed to protrude through the opening c when so set by means of the lever E. Said opening or outlet is then closed. The lever E has a jointed connection, d, with the lower end of 40 the valve-stem B', as shown in Fig. 1. The pivotal connection or fulcrum of the lever E is formed by means of the hinges G, which are suspended by a joint from the lugs e (seen in Fig. 2) on the lower side of the base a. In 45 the bottom of said air-chamber is an opening, f, which is covered by the valve C. This valve

is on and guided by the valve-stem B' and lever D, and is operated by the lever D also, which lever is pivotally connected with the lugs e at h by the same jointed connection 55 which forms the hinge G. The free end of the lever E is set or arranged in the notches of the corrugated spring-guides I when the valve C is adjusted to close the opening f. This opening is used as an outlet for the discharge of 60 cinders or ashes which may drop into the air-chamber from the fire above through the opening c.

At intervals, when the fire is lowering—that is, when the blast is retarded, owing to the 65 accumulation of cinders in the air-chamber—then the lever D is disengaged from the notch of the bar H, Fig. 1, and the lever E raised toward the lever D, as indicated by the dotted line g, which movements admit of the valves 70 B C being moved from their seats. As the valve C is moved from its seat and the valve B lowered from its seat, one is enabled to free the air-chamber and the fire from cinders and ashes through the openings c and f, in order 75 to induce a free blast and active fire for use. On closing the valve C then the valve B can be set according to the amount of blast required. By means of the corrugated spring-guide I, secured to the lever D, the lever E may 80 be set and retained in the notches or catches of said guide and held in position with relation to the valve B, according to the volume or draft of air required for the fire. The said guide I consists of spring-loops, through which 85 the lever vibrates, the projections i, Fig. 3, on the inside of the guide between the loops restraining the passage of the lever E to such an extent that force is required to swing the lever up or down, so that the lever is held in the 90 position required. It is thus that the blast passing through the opening c is under the described controllable devices and directed to the fire. On lowering the valve B slightly from its seat, only a small current of air is 95 given to the fire, whereas, when required, the valve can be so opened as to use the full force of the blast.

It is essential to the effectiveness of said tuyere-iron that the air-chamber A and valve 100 B be so proportioned in relation to each other as to allow of a free and open passage of air

from the chamber through the opening *c* to the fire. The valve *B* and its stem are preferably made hollow, as seen in Fig. 1, to admit a current of air through the stem and valve, by means of which the said parts are held cool and of light weight for operation.

In the apex of the valve *B* are one or more holes, *j*, for the eduction of air from its induction *k* at the lower end of the stem. This passage of air through the valve and stem is induced by the strong air-current flowing through the opening *c* at the crown of the chamber *A*. On lowering or opening the valve *B*, the force of air passing through said valve-opening *c*, being in contact with the fire, causes a suction upon the holes *j*, thereby inducing a partial vacuum in the chamber *l* of the valve *B*, which vacuum is constantly supplied with exterior air through the tubular stem *B'* of the valve *B*; hence the induction of air through the stem and valve is constant with its eduction through the holes *j*, Figs. 1 and 3.

If it is required to keep the coal ignited after the blast is shut off from the air-chamber, then the lever *D* is disengaged from the notch in the bar *H* and the valve *C* moved down to induce a current of air through opening *f* in the bottom of the air-chamber, which will sustain ordinarily enough fire until the usual air-blast is again set in action.

What I claim, and desire to secure by Letters Patent, is—

1. A tuyere-iron consisting of the valves *B* and *C* and levers *D* and *E*, in combination with the air-chamber constructed as described, with the said valve *B* adapted to the chamber and the opening *c* in the crown thereof, of the valve *C* having a seat in the base of said chamber and sliding upon the tubular stem of the valve *B*, arranged substantially as set forth, for the purpose described.

2. In combination with the levers *D* *E*, hollow valve *B*, having a tubular stem, and valve *C*, of the air-chamber, arranged as shown in relation to said valve *B*, of the guide *I*, secured to the lever *D* and inclosing the lever *E*, with projections *t* at the inside thereof, forming stops to arrest and hold said lever *E* at divers points within the guide, as set forth.

3. In a tuyere-iron, the combination of the air-chamber, a hollow valve, *B*, with a tubular stem, and having one or more air-passages in the apex of said valve, of the valve *C*, surrounding the tubular stem, and the levers *D* *E*, arranged in conjoint and operative relation with said valves, in the manner and for the purpose substantially as set forth.

In testimony whereof I affix my signature in presence of two witnesses.

BERNARD McGRODER.
